UNITED STATES PATENT OFFICE.

CHARLES B. SWINK, OF MUSKOGEE, INDIAN TERRITORY.

PRINTING-PRESS.

No. 824,889.

Specification of Letters Patent.

Patented July 3, 1906.

Application filed September 29, 1905. Serial No. 280,586.

To all whom it may concern:

Be it known that I, CHARLES B. SWINK, a citizen of the United States, residing at Muskogee, Creek Nation, Indian Territory, have 5 invented certain new and useful Improvements in Printing-Presses, of which the following is a specification, reference being had to the accompanying drawings, forming a part hereof.

10 This invention relates to printing-presses in which the bed-plate reciprocates and the cylinder revolves, and more especially to presses of this kind in which the reciprocating bed is actuated by a crank-arm or its equivalent. In such presses the movement of the reciprocating bed-plate is not uniform, but varies from slow speed to high speed. Consequently when the cylinder and bed-plate are 15 in operative contact during approximately two-thirds of the bed-plate's movement in one direction the cylinder must rotate with a varying speed, while during the balance of the movement in the first direction and the movement in the opposite direction, 20 when the cylinder and bed-plate are not in operative contact, the cylinder may rotate at a uniform speed.

25 The object of the present invention is to provide improved means for lifting the impression-cylinder from operative contact with the reciprocating bed-plate during its movement in one direction, and, furthermore, to provide improved means for driving the impression-cylinder at a varying speed then 30 it is in operative contact with the bed-plate.

35 One object particularly in view is to permit the gears which drive the cylinder to be constantly in mesh, so that there shall be no possibility of a harmful change of the relations 40 between the cylinder and the bed-plate.

45 The invention will be more fully explained hereinafter with reference to the accompanying drawings, in which it is illustrated, and in which—

50 Figure 1 is a top plan view of a press which embodies the present improvements, parts being broken out and removed to show details. Fig. 2 is a view in longitudinal section on the plane indicated by the line 2 2 of Fig.

55 Fig. 3 is a partial view in section on the plane indicated by the line 3 3 of Fig. 1. Fig. 4 is a view in transverse section on the plane indicated by the line 4 4 of Fig. 1.

The frame *a* of the press is suitably constructed to support the reciprocating bed-

plate *b* and the other working parts. The present invention is not particularly concerned with the precise form of mechanism for reciprocating the bed-plate; but, as shown in the drawings, the main shaft *c*, having 60 suitable driving-pulleys *c'* and balance-wheel *c''*, is provided with a gear *d*, which engages a gear *e* upon a driving-shaft *e'*. A crank-arm *e''* is likewise secured upon the shaft *e'* and is provided with a wrist-pin *e''*, which engages a 65 vertical slotted arm or bracket *b'*, secured to the bed-plate *b*, whereby as the shaft *e'* is rotated the bed-plate is reciprocated. As the wrist-pin *e''* passes the horizontal plane of its center of motion the direction of movement 70 of the bed-plate is reversed and its speed is slowest and at the intermediate points its speed attains the maximum. So far as the present invention is concerned any other similar or suitable means might be employed 75 for reciprocating the bed-plate, it being understood that the means presently to be described for rotating the impression-cylinder are devised with especial reference to a varying speed of movement of the bed-plate, such 80 as would be produced by the means described.

The impression-cylinder *f* has its shaft *f'* mounted in vertically movable bearing-blocks *f''*, guided in suitable ways *f'''*. Compression-springs *f''* act normally to raise the 85 blocks *f''* and to lift the impression-cylinder *f* from the type carried by the bed-plate *b*. The devices which control the lifting of the cylinder and bring it down upon the type at the proper time comprise the following instruments, viz: a cam *g*, mounted on the crank-shaft *e'*; arms *g'*, cooperating with the cam and connected by a link *g''*, so that they shall move together; a rack-bar *g''*, which is pivotally connected to an extension of one 90 of the arms *g'*, and a shaft *h*, having a segment *h'*, engaged by the rack-bar *g''*, and eccentrics *h''*, which are engaged by links *h'''*, the latter being pivotally connected to the vertically-moving blocks *f''*. The cam *g* is suitably proportioned, as shown particularly in Fig. 3, and is suitably positioned with reference to the crank-arm *e''*, so that before the bed-plate has finished its movement in one direction, as to the right in Fig. 2, the shaft *h* 100 is rotated to permit the cylinder to rise upon the compression-springs *f''*, and after the close of the movement of the bed-plate in the opposite direction the cam operates to draw the blocks *f''* downward against the pressure 105 110

of the springs f^4 and bring the impression-cylinder into operative contact with the bed-plate.

The impression-cylinder f is driven in synchronization with the crank-shaft e' ; but its speed of rotation is varied in proportion to the speed of movement of the bed-plate so long as the impression-cylinder is in operative contact with the bed-plate, as shown in Fig. 2, while at other times the cylinder is permitted to rotate at a uniform speed. To accomplish this result without permitting the gears which rotate the cylinder to become disengaged, there is mounted upon the shaft e' an irregular gear i , a portion of its periphery, as shown, having a uniform radius, while another portion of its periphery has an increasing radius from the beginning to the middle of such portion and a decreasing radius from the middle to the end of such portion. A complementary gear k engages constantly with the gear i and is secured upon a shaft k' , which is mounted for rotation in bearings in the press-frame. The shaft k' also has secured thereto a gear m , which meshes with an idler n , (if an idler be used,) also mounted for rotation on a stud secured in the press-frame, and the idler engages a gear o , fixed on the shaft f' of the impression-cylinder f . The vertical movement of the gear o is slight and is sufficiently accommodated by deeply-cut teeth on two of the gears, as m and n , so that the cylinder f has the varying speed of rotation during its two-thirds revolution, which is required by the varying speed of movement of the bed-plate with which it is then in contact, and has a regular speed during the remaining part and the next revolution, when the cylinder is out of contact with the bed-plate, and at the same time all of the gears which are involved in the rotation of the cylinder remain in constant engagement.

The mode of operation of the improved press will be clearly understood without further explanation, and it will also be seen that the shifting of the cylinder from uniform speed of rotation to non-uniform speed of rotation is timed according to the time of the printing stroke and that while the cylinder is in contact with the bed-plate it rotates at a speed exactly corresponding to that of the bed-plate. Furthermore, notwithstanding the vertical movement of the cylinder its driving-gears remain always in mesh and the cylinder retains always its proper relation to the bed-plate. The cylinder-lift mechanism, as will be noted, is simple in construction and direct in operation and lends itself readily to the desired movements.

I claim as my invention—

1. In a press, the combination of a reciprocating bed-plate, a crank to drive the same whereby the bed-plate upon each reciprocation is gradually started, attains a maximum

velocity and gradually stops, a cylinder, a train of gears to drive the cylinder including a mated pair of irregular gears whereby the cylinder may be driven in harmony with the bed-plate during the printing operation, and means to impart motion to said crank and to said train of gears.

2. In a press, the combination of a reciprocating bed-plate, a crank to drive the same whereby the bed-plate upon each reciprocation is gradually started, attains a maximum velocity and gradually stops, a cylinder, a train of gears to drive the cylinder including a mated pair of irregular gears whereby the cylinder may be driven in harmony with the bed-plate during the printing operation, a shaft upon which said crank and one of said train of gears are mounted, and means to impart motion to said crank.

3. In a press, the combination of a reciprocating bed-plate, a crank to drive the same whereby the bed-plate upon each reciprocation is gradually started, attains a maximum velocity and gradually stops, a cylinder, a train of gears to drive the cylinder including a mated pair of irregular gears whereby the cylinder may be driven in harmony with the bed-plate during the printing operation, movable bearings for the cylinder, an eccentric-shaft, links connecting the eccentrics thereon with said movable bearings, and means for rotating said eccentric-shaft in harmony with the reciprocation of the bed-plate.

4. In a press, the combination of a reciprocating bed-plate, a crank to drive the same whereby the bed-plate upon each reciprocation is gradually started, attains a maximum velocity and gradually stops, a cylinder, a train of gears to drive the cylinder including a mated pair of irregular gears whereby the cylinder may be driven in harmony with the bed-plate during the printing operation, and also including gears with deeply-cut teeth whereby said train of gears will remain constantly in mesh, movable bearings for the cylinder, an eccentric-shaft, links connecting the eccentrics thereon with said movable bearings, a driving-shaft upon which said crank and one of the train of gears are mounted, a cam on said shaft, and means actuated by said cam for rotating the eccentric-shaft in harmony with the movements of the bed-plate.

5. In a press, the combination of a cylinder, a bed-plate, a driving-shaft, means actuated therefrom to reciprocate the bed-plate at a varying speed and a train of gears constantly in mesh between the driving-shaft and the cylinder including a mated pair of irregular gears whereby the cylinder is rotated at a varying speed in harmony with the movements of the bed-plate, substantially as described.

6. In a press, the combination of a cylin-

der, a bed-plate, a driving-shaft, means actuated by the driving-shaft to reciprocate the bed-plate with a varying speed, a train of gears constantly in mesh between the driving-shaft and the cylinder, including a mated pair of irregular gears whereby the cylinder is rotated at a varying speed in harmony with the movements of the bed-plate, and means to separate the cylinder and the bed-plate during reciprocation of the latter in one direction, substantially as described.

7. In a press, the combination of a cylinder, a bed-plate, a driving-shaft, means actuated by the driving-shaft to reciprocate the bed-plate at a varying speed, a train of gears between the driving-shaft and the cylinder including a mated pair of irregular gears, each of said irregular gears having one portion of its periphery of uniform radius and the other portion of its periphery of varying radius, and means to separate the cylinder

and the bed-plate while the uniform portions of said irregular gears are in engagement, substantially as described.

8. In a press, the combination of a cylinder, a bed-plate, a driving-shaft, means actuated by said driving-shaft to reciprocate the bed-plate at a varying speed, a train of gears between the driving-shaft and the cylinder including a mated pair of irregular gears, a cam on said shaft, two arms connected together and devices controlled by said arms to separate the cylinder and bed-plate and to bring them again into operative contact, substantially as described.

This specification signed and witnessed this 25th day of September, 1905.

CHARLES B. SWINK.
